United States Patent Office

Des. 185,990
Patented Aug. 25, 1959

185,990

BEVERAGE CASE

Carl H. Dickman, Scranton, and Carmin A. Castellano,
Clarks Summit, Pa., assignors to Consolidated Molded
Products Corporation, Scranton, Pa., a corporation of Delaware

Application May 6, 1959, Serial No. 55,792

Term of patent 14 years

(Cl. D58—5)

FIG. 1.

Des. 185,990
PAGE 2

FIG. 2.

FIG.4.

Both ends and both sides of the beverage case are as shown in Figures 3 and 4, respectively.

We claim:

The ornamental design for a beverage case, as shown and described.
